UNITED STATES PATENT OFFICE

HAZLEHURST R. NOYES, OF LOS ANGELES, CALIFORNIA, ASSIGNOR TO GERTRUDE E. NOYES, OF LOS ANGELES, CALIFORNIA

WINDOW SCREEN AND STRUCTURE

Application filed October 24, 1930. Serial No. 490,883.

This invention relates to windows and window screens, and more particularly to what will herein be termed an interchangeable screen; that is, a screen that will automatically move into the position occupied by a window upon the removal of the window from that position, and vice versa.

Window screens are now quite well-known and have been used for some time; however, the use of these prior known screens is open to many objections. For double hung windows, it has been common for example to use a removable frame disposed above or below the opened window and held in place between an edge of the window and the frame; or else a screen fitting in the frame on the outside of the window. When the removable screens were used, it was always necessary to remove the screen each time the closing of the window was desired. This screen when in use occupied but half of the window frame or sash. In the use of casement windows, the screen has always presented a problem. If the window swung outward, the screen could not be placed outside of the frame, but only inside; and some provisions had to be made to move the screen so as to be able to manipulate the window.

It is an object of this invention to provide a window structure which obviates the above mentioned objections. I accomplish this by means of a screen having a size equal to the size of the window and which is mechanically secured thereto so that a movement of the window out of the window frame structure will automatically cause the screen to occupy the position formerly occupied by the window, and the window to occupy the position formerly occupied by the screen. In this manner, the screening of a complete window frame structure without interference from the window is made possible.

It is a further object of this invention to provide a screen which can be interchanged with a window at will without necessitating the complete removal of the screen from the window structure as in the screens of the prior art.

It is a further object of this invention to provide a screen which can be readily made

to occupy the position formerly occupied by the window and which when not in active use, will be disposed in a recess formed within the window structure or framework of the walls of a building, and thus be protected from the deleterious effect of the elements.

It is a further object of this invention to provide a novel means of locking the windows or screens so that they cannot be opened from the exterior side, and which also acts to prevent the unassisted movement of the window or screen out of the window structure.

It is a further object of this invention to provide a device of this character of a simple and practical construction, which is efficient and reliable in performance, neat and attractive in appearance, relatively inexpensive to manufacture and which may be quickly installed in a window frame structure without necessitating any great changes in the details of construction thereof.

My invention possesses many other advantages, and has other objects which may be made more easily apparent from a consideration of one embodiment of my invention. For this purpose I have shown a form in the drawings accompanying and forming part of the present specification. I shall now proceed to describe this form in detail, which illustrates the general principles of my invention; but it is to be understood that this detailed description is not to be taken in a limiting sense, since the scope of my invention is best defined by the appended claims.

Referring to the drawings:

Figure 1 is a front elevation, viewed from inside of a room, of an interchangeable screen structure embodying my invention, showing its relation with a window and a window frame structure when in active position;

Fig. 2 is an enlarged detailed elevation of a screen embodying my invention, viewed from the inside of a room, parts of the wall being broken away to show the mechanical connection between the window and screen, and the mode of operation thereof;

Fig. 3 is a section taken substantially along the plane 3-3 of Fig. 2; and

Fig. 4 is a section taken substantially along the plane 4-4 of Fig. 2.

My invention is not limited to any details of design or construction or any specific window frame structure or wall structure, and accordingly only so much of a window frame structure as will aid in the proper understanding of this invention is shown and will be described.

It is common, of course, to provide a window frame in which the window as well as a screen can be supported. In the present instance the window frame is so arranged that the screen and the window can be alternately moved into position with respect to the opening of the frame, in a manner to be herein-after described. The frame utilizes a pair of spaced rectangles, one arranged on the interior side of a wall structure and the other on the exterior side of the wall structure. Thus as shown clearly in Figs. 1 and 3, the outer frame structure can include the top and bottom members 11 and 13 supported on the outside of the wall 9. The bottom member 13 is usually referred to as a window sill. Side members serve to provide a complete rectangle forming the exterior of the window frame. The interior of the frame is correspondingly formed by the top and bottom members 10 and 12 and side members 14 and 15. In the present instance a double frame is indicated as by the provision of a central partition 16 extending entirely through both the interior and exterior frames.

The windows referred to as a whole as by 17, comprise a sash composed of top and bottom sash bars 18, 19 and side bars 20. This sash may have a window glass secured therein in any desirable manner. As shown in the drawings, the sash is divided in this instance into four sections by cross connecting bars 21 and 22 and thus provide a window in which four glass plates 23 are used. These windows, of which there are two, are adapted to fit into the two sections of the framework of the window structure in a manner readily apparent from the drawings.

Screens 24 are secured to the frameworks in any desirable manner as by anchoring them between the composite material forming the frames (see Fig. 4). These frames 50 are of the same size as the window sash, and comprise top and bottom members 25, 26 and side members 27. These frames, when not in use in the window frame structure are maintained in pockets or recesses formed in the 55 wall structure between the window structure and the supports 28, 29. Recesses or pockets 30 and 31 are also formed between the horizontal beams 32 and 33 and the tops and bottoms of the window frame structure and 60 screen frames for a purpose to be hereinafter described. The beams 32 and 33, as well as members 28, 29, form part of the reinforcing of the wall structure surrounding the windows and screens.

65 The screens 24 are mechanically connected

to the windows 17 and are readily interchangeable therewith in the window structure. This alternation of the screen and window is arranged to be automatic in response to the movement of one of them. Thus a simple mechanical arrangement of pivoted levers can be used as the connecting mechanism. Levers or bars 34, 35 are pivotally connected to the upper ends of the frames of the screens and windows as at 36, 37, 38 and 39. These bars are also pivotally connected at an intermediate point to a stationary angle iron or support 40 as at 41 and 42. (See Figs. 2 and 3.) This angle iron 40 is secured to the lower surface of the top of the window frame structure. The lower ends of the sash and screen frame are similarly connected by a lever or bar 43 which is pivotally secured to but one end as at 44, 45. This lever is also pivotally secured at an intermediate point as at 46 to an angle iron 47. (See Fig. 4.) The angle iron 47 is fixedly secured to the window sill 13 and is coextensive therewith. A knob or handle 48 is secured to one of the side frames of either the windows or screens and thus provides a means for facilitating the interchangeability of the screen for a window or vice versa. In the drawings, the knob 48 is shown as being secured to the side frame of the screens.

The operation of the device is readily apparent from the foregoing. Thus, viewing Fig. 2, let us assume that the screen 24 was in position between the top and bottom 10, 11, the side frame 15, and the partition 16, the top edge engaging the angle iron 40; and that it was intended to move the screen in the pocket or recess as shown in dotted lines in Fig. 1. Fig. 2 represents the position the parts assume when the screen is slightly more than half way in the recess. Thus, by grasping the knob 48 and pulling downwardly thereon to move the top edge of the screen away from angle iron 40 and until the levers 34, 35 and 43 are parallel to the side frame 15, and then pushing upwardly thereon until the levers are parallel with the top and bottom 10, 12, the parts will assume the position shown in Fig. 1. The window 17 will move in the direction of the arrows 50 (Fig. 2) along a circle having as a radius, the distance between the pivot of a lever, and the point of connection to the sash. The operation of the device is the reverse of that heretofore described if the window instead of the screen is to be moved into the assumed position. It is readily apparent that by means of this arrangement, the interchangeability of the screen for a window or vice versa may be done at will, and the screen when in the window structure is unobstructed, and when in the recess (see Fig. 2), is protected from the elements. The movement of the screens and window is limited to the described bounds by means of the angle irons 40 and 47 which

present abutments to one of the ends of the screens and windows respectively. The other ends of the screens and windows are permitted to freely move into the recesses 30 and 31 between the framework of the window structure.

In order to lock the window or screens when in position in the window structure so as to prevent the opening thereof from the outside, I provide locking devices 49, 49 which are retained in recesses 50, 50 formed in the sides of the partition member 16. These locking devices are hingedly secured at the lower ends to the partition 16 as at 51, and are of a size which permits their abutment against the side frame of the screen in the recess when folded down (see Fig. 1). These locking devices also act to prevent the unassisted movement of the window out of the window structure.

Although I have described but one mechanical arrangement for interchanging the screens and windows, this invention should not be limited thereto as it is equally applicable to any known mechanical means for performing the above set forth operations. It is to be further understood that this invention is not limited to any specific materials for making the frames, etc., as it is equally applicable to wood, metal, alloys, etc., although in the drawings I show wood frames.

I claim:

1. In combination with a window structure and a window, a screen, and pivoted means connecting the screen to the window, said means being characterized whereby a movement of the window out of the window structure will automatically cause the screen to occupy the position in the window structure formerly occupied by the window.

2. In combination with a window structure and a window, a screen, and reversible acting pivoted means connecting the screen to the window, said means being characterized whereby a movement of the window out of the window structure will automatically cause the screen to occupy the position in the window structure formerly occupied by the window.

3. In combination with a window structure and a window, a screen, and reversible acting means connecting the screen to the window, said means being characterized whereby a movement of the window out of the window structure will automatically cause the screen to occupy the position in the window structure formerly occupied by the window.

4. In combination with a window structure and a window, a screen having a size substantially equal to the size of the window, and means connecting the screen to the window, said means comprising levers pivotally connecting the ends of the window and

screen, said levers being pivotally connected to a portion of the window structure whereby a movement of the window out of the window structure will automatically cause the screen to occupy the position in the window structure formerly occupied by the window.

5. In combination with a window structure and a window, a screen having a size substantially equal to the size of the window, and reversible acting means connecting the screen to the window, said means comprising levers pivotally connecting the top and bottom ends of the window and screen, said levers being pivotally connected at an intermediate point to the window structure whereby a movement of the window out of the window structure will automatically cause the screen to occupy the position in the window structure formerly occupied by the window.

6. In combination with a window structure and a window, a screen having a size substantially equal to the size of the window, and reversible acting means connecting the screen to the window, said means comprising levers pivotally connecting the top ends of the screen and window, and a lever pivotally connecting one of the bottom ends of the screen and window, said levers being pivotally connected at an intermediate point to the window structure whereby a movement of the window out of the window structure will automatically cause the screen to occupy the position in the window structure formerly occupied by the window.

7. In combination with a window structure and a window, a screen, reversible acting means connecting the screen to the window, said means being characterized whereby a movement of the window out of the window structure will automatically cause the screen to occupy the position formerly occupied by the window, and means locking the window or screen in the window structure, said means acting to prevent the unassisted movement of the window or screen out of the window structure.

8. In the combination set out in claim 1, and means locking the window in place, said means also acting to prevent the unassisted movement of the window out of the window structure.

9. In the combination set out in claim 6, and means locking the window in place, said means also acting to prevent the unassisted movement of the window out of the window structure.

10. In combination with a window structure and a window, a screen, pivoted means connecting the screen to the window, said means being characterized whereby a movement of the window out of the window structure will automatically cause the screen to occupy the position in the window structure formerly occupied by the window, and means

limiting the respective movements of the screen and the window.

11. In a window structure having a window frame and a recess laterally thereof, a window and a screen, said window and said screen normally residing respectively in said window frame and said recess, and means connecting said window and screen, said means being characterized whereby a movement of the window out of the window frame will cause the screen to occupy the position formerly occupied by the window.

12. In a window structure having a window frame and a recess laterally thereof, a window and a screen said window and said screen normally residing respectively in said window frame and said recess, and means connecting said window and screen, whereby a movement of the window out of the window frame will cause the screen to occupy the position formerly occupied by the window, and the window then occupies the position formerly occupied by the screen.

13. In combination, a window structure, a screen structure, said structures coacting with a window opening, and connections between the structures to reverse their positions with respect to the opening.

14. In combination, a frame for defining a wall opening, a pair of structures alternately coacting with said opening, means for mounting each of said structures for transverse movement with respect to said opening, said means including a mechanism for reversing the relative positions of the structures with respect to the opening.

In testimony whereof, I have subscribed my name.

HAZLEHURST R. NOYES.
